United States Patent

Des. 238,485
Patented Jan. 20, 1976

238,485

QUADRICYCLE

Charles David Baldwin, Toledo, Ohio, assignor to Toucon Manufacturing Inc., Toledo, Ohio

Filed Oct. 29, 1974, Ser. No. 518,482

Term of patent 14 years

Int. Cl. D12—11

U.S. Cl. D12—107

FIG. 1 is a top, front perspective of a quadricycle embodying my new design;

FIG. 2 is a side elevational view thereof;

FIG. 3 is a top plan view thereof;

FIG. 4 is a front elevational view thereof; and

FIG. 5 is a rear elevational view thereof.

I claim:

The ornamental design for a quadricycle, as shown.
